UNITED STATES PATENT OFFICE.

JOHN B. HALBERT, OF MAITLAND, FLORIDA.

RATCHET-WRENCH.

SPECIFICATION forming part of Letters Patent No. 268,792, dated December 12, 1882.

Application filed August 1, 1882. (No model.)

To all whom it may concern:

Be it known that I, JOHN B. HALBERT, a citizen of the United States, residing at Maitland, in the county of Orange and State of Florida, have invented certain new and useful Improvements in Ratchet-Wrenches; and I do declare the following to be a full, clear, and exact description of the invention, such as will enable others skilled in the art to which it appertains to make and use the same, reference being had to the accompanying drawings, and to the letters and figures of reference marked thereon, which form a part of this specification.

This invention has relation to improvements in ratchet-wrenches; and it consists essentially in the combination, construction, and arrangement of the several parts, as will be hereinafter fully described, and specifically pointed out in the claims.

20 In the drawings, Figure 1 is a side view, part in section, Fig. 2 is a plan view, and Figs. 3, 4, and 5 are detail views, of a wrench constructed according to my invention.

A represents the rotary head. It is formed with the angular opening a extending entirely through it for convenience in removing bolts or nuts, and also to render the wrench suitable for turning nuts on or off by simply reversing the same, so as to work with one or the other end of the rotary head. This opening may be made square, hexagonal, or any other shape desired, and, where it is necessary so to do, different heads with the different-formed openings may be provided.

35 a' represents a peripheral ring, formed on the rotary head midway its ends, and made larger than the main portion of the head, so as to provide shoulders on the opposite sides thereof, for the purpose hereinafter described. In the center of this ring I form the ratchet-teeth a^2 , extending entirely around the rotary head A. On either side of the teeth a^2 on the ring a' , I leave annular bearings a^3 for the open portion or ring on handle, as will be described.

40 b b' are rings or flanges abutted against the side of ring a' , and projected outwardly to form side bearings for the handle-ring, as will be described. I prefer to form the ring or flange b as part of the rotary head, and to screw the shoulder b' on the opposite side, for which I

provide the same with a screw-thread, b^2 , as shown in Fig. 3. It will be understood, however, that both rings b b' could be made removable, as is the case with ring b' . By forming the ring a' larger than the main portion of the head A, as shown, and forming the ratchet-teeth in the center of same, I provide abutting shoulders for the rings or flanges b b' on either side of the ring a' , and also bearings a^3 on either side of the ratchet teeth to receive the handle-ring, hereinafter described. The rings b b' are sloped, beginning almost with their peripheries, down to the main portion of the rotary head, and I form them especially to fit under the tread of a railway-track, as I have designed my wrench particularly for such work, and I extend the rotary head on either side of the enlarged peripheral ring a' far enough to permit either end to fit around a bolt-head or nut secured in the hollow of the rail, between the tread and base, and yet permit the handle, hereinafter described, to work in a line parallel with the rail.

55 B represents the handle. It is composed of the working-arm c and the ring c' . The ring c' corresponds in width to the ring a' on rotary head, and it is adapted to be placed around said ring and secured between the flanges b b' , as shown in Fig. 2.

60 c^2 represents a portion of the arm c near its connection with the ring c' , which portion is larger than arm c , as shown in Fig. 1.

65 d represents a slot cut through ring c' , and continued in a groove or mortise, d^2 , in portion c^2 of the handle, adapted to receive and permit the necessary movement of the pawl, hereinafter described. The forward wall of the slot d is inclined inward at an angle, as shown, for the purpose of better securing the pawl in the ring c' , as will be described.

70 d' is a mortise cut in arm c at its joint with portion c' . The mortise is not as deep as the mortise formed in portion c' , and it is connected with the said mortise by an opening, through which is passed the spring, hereinafter described. The bridge or cross-piece c^3 of portion c^2 forms a covering and a protector for that portion of the spring between its point of connection with the handle and with the pawl. Through the walls of portion c' left by

the mortise d^2 , I form holes for the pawl-pivot pin e .
 f represents the pawl. On its upper side it is shaped to conform to the ring c' and portion c^2 of handle, as shown in Fig. 1. At its forward end it is constructed with the points $f^1 f^2$. The point f^1 engages the teeth of the ratchet a^2 , the motion of the pawl f being indicated in dotted lines, Fig. 1. The upper face of the point f^1 corresponds to the angle at which the forward wall of the slot d is cut away, as described, and the inner edge of the pawl is made longer than the outer opening of the slot d , as shown, and it is thus impossible to withdraw the pawl from the handle-ring c' without first removing the rotary head and pushing the pawl inward, so in case of breakage of the pivotal pin the pawl will not drop out and be lost. The length of the pawl from its rear end to the end of the points $f^1 f^2$ is greater than the slot d , and the pawl can only be removed from the handle through the opening in ring c' . There is therefore no danger of the pawl dropping out and being lost by the breaking or slipping out of its pivoting-pin e .
 f^3 is an opening through the pawl f near its rear, adapted to receive the pin e . f^4 is a small slot in the rear end of the pawl.
 g represents the spring. Its end is passed under the bridge c^3 and driven into the mortise d' . In order to secure the spring in place, I make its rear portion slightly wider than the mortise d' , and drive it into place in the said mortise, where, when so applied, it is securely held in place. The forward end of the spring rests in the slot f^4 in end of pawl and presses

the point f^1 down against the ratchet. When the spring is broken or becomes otherwise ineffectual it can be removed by removing the pawl and inserting the point of a chisel into the mortise d' and driving the spring out.

The operation of my wrench is readily understood on reference to the drawings.

Having thus described my invention, what I claim, and desire to secure by Letters Patent, is—

1. In a ratchet-wrench, the combination of the rotary head A , having annular ratchet a^2 , the handle B , provided with ring c' , and constructed with the slot d and mortise d' , communicating through an opening formed under the bridge c^3 , the pawl f , and the spring g , secured in position within the mortise d' and under the bridge c^3 , substantially as and for the purposes set forth.

2. The combination of the rotary head A , provided with annular ratchet a^2 , the handle-ring c' , placed on the rotary head, and constructed with the slot d , opening immediately over the ratchet a^2 , with its forward wall inclined inward at an angle, as shown, and the pawl f , having a point, f^1 , projected from its inner lower edge below the ring c' , whereby when it is raised the said point will engage on the front wall of the slot d , substantially as set forth.

In testimony whereof I affix my signature in presence of two witnesses.

JOHN B. HALBERT.
